UNITED STATES PATENT OFFICE.

ALVA J. CARTER, OF CHICAGO, ILLINOIS, ASSIGNOR TO CARTER RADIO COMPANY, OF CHICAGO, ILLINOIS, A CORPORATION OF ILLINOIS.

JACK.

Application filed May 24, 1926. Serial No. 111,319.

My invention relates to jacks and more particularly to jacks which are used for the interconnection of electric circuits, such jacks being used in a variety of ways in connection with plugs.

In accordance with my invention, I have provided a jack of this nature which, while not limited to such use, is of particular adaptability in connection with its use upon panels; in one of its forms it is of particular utility in connection with radio circuits.

In the construction of jacks for use in connection with radio apparatus, it is necessary to build a rather compact type of jack and yet at the same time one which, by reason of the basic nature of its construction, lends itself readily for use with different circuits by reason of the fact that the plug may be provided with all manner and sorts of connecting springs and practically without regard to the number of such springs employed.

It is a prime object of my invention in the provision of a jack of this kind to insure adequate insulating qualities and to secure these insulating qualities by reason of the structural design of the jack itself. Heretofore jacks of this nature have been constructed in which an insulating tube or sleeve is relied on to provide the proper insulating qualities. The use of such a sleeve introduces assembling and other difficulties. In accordance with my invention I eliminate the use of such an insulating sleeve altogether.

I will describe one form which my invention may take more in detail by referring to the accompanying drawing illustrating one embodiment thereof in which:

Fig. 1 is a transverse sectional view of a jack constructed in accordance with my invention, as mounted upon a panel;

Fig. 2 is a rear view thereof; and

Figs. 3 and 4 are side views respectively of two of the contact springs.

My improved jack consists of a basic rounded metallic sleeve portion 10 having at its right hand extremity a screw-threaded portion 11 which in co-operation with the nut 12 and the interposition of the washer 13 is designed for mounting purpose upon a panel 14. The sleeve portion 10 also preferably has a shoulder 15 which abuts the rear face of the panel, this shoulder and nut

holding the jack structure in position upon the panel. The basic sleeve portion 10 also has a rearwardly extending thimble portion 16 which insulatingly carries one or more connecting springs.

In the illustration I show my improved jack as having three connecting springs respectively the springs 17, 18, and 19. I am using the term springs to indicate these contacts or connecting elements because that is a term generally used in the art although the connector 17 really requires no spring action to perform its function as will be presently apparent. It might also be said that the element 18, in a certain manner of constructing the device would not necessarily require spring action to properly function. The element 17 as will presently be seen, serves merely as a connector, the same being provided with a hole 20 to which a conductor may be soldered. This element 17 consists of a plate-like portion 21 and its extending arm. The elements 18 and 19 respectively have protruding connectors 22 and 23 respectively as will be presently explained.

In accordance with my invention I construct the contact spring 19, for instance, with a cup-shaped base 24 which cup-shaped base has an annular flange 25. The base 24 is also provided with a hole which as is clearly apparent from Fig. 1 is larger than the outer diameter of the thimble 16. In a similar manner the element 18 has a hole which is also larger than the outer diameter of the thimble 16 and has a cup-shaped base 26 having an annular flange 27. Now in order to mount these two elements 18 and 19 in place, I first superpose a washer of insulating material 28 upon the thimble 16 and arrange the same so that it abuts the collar 15. I then place the element 19 into its position as shown in Fig. 1 and insert in place an insulating washer and distance piece 29. This washer 29 has a central opening which fits the outer circumference of the thimble 16 with reasonable snugness. This washer 29 has a sufficiently large outer diameter so that it fits snugly the interior surface of the flange 25. This washer 29 is made of suitable material which retains its size sufficiently for practical purpose within the normal ranges of temperature and humidity. It will thus be seen that the

washer 29 prevents the element 19 from touching the thimble 16. The cup-shaped portion of the element 19 is thus permanently held in position concentrically to the 5 thimble 16, the two washers 28 and 29 completing the insulating mounting.

In a similar manner the cup-shaped portion of the element 18 is held in its concentric and insulating relationship by the washer 10 30. Thereupon the element 17 is superposed upon the washer 30 and the extremity of the thimble 16 is upset as shown at 31 to hold all of the parts together, the completed jack thus having means whereby an 15 electrical connection may be made to the thimble through the interposition of the element 17 and whereby electrical connection may be made to the insulatingly mounted 20 elements 18 and 19 through the agency of the connecting elements 22 and 23 respectively.

The elements 18 and 19 as shown are so arranged that their extremities normally contact and that they are forced out of contact whenever the plug is inserted in the thimble of the jack. It will thus be seen that I have provided a jack structure in which the parts can be very easily and simply assembled together in permanent 25 relationship and with the necessary insulating 30 qualities.

From what has been thus described, the nature of my invention will be clear to those skilled in the art, and, having thus 35 described one form which my invention may take, what I claim as new and desire to secure by United States Letters Patent is:

1. A jack of the character described having a metallic thimble portion, a contact element 40 insulatingly mounted thereon, said contact element having an opening encircling said thimble portion larger in diameter than said thimble portion, an insulating washer snugly encircling said thimble portion, and peripheral means on said contact element co-operating with said washer to prevent 45 said contact element from touching said thimble.

2. A jack of the character described having a hollow metallic thimble portion through which a connecting plug is adapted 50 to project, a contact element insulatingly mounted thereon, said contact element having an opening encircling said hollow thimble portion larger in diameter than said thimble portion, an insulating washer snugly encircling said thimble portion, and means 55 on said contact element co-operating with said washer to prevent said contact element from touching said thimble.

3. A jack of the character described having a metallic thimble portion, a contact element insulatingly mounted thereon, said contact element having an opening encircling 60 said thimble portion larger in diameter than

said thimble portion, an insulating washer snugly encircling said thimble portion, peripheral means on said contact element co-operating with said washer to prevent said contact element from touching said thimble, 70 and an insulating abutment for said element on the side of said element opposite to the side co-operating with said washer.

4. A jack of the character described having a metallic thimble portion, a contact element insulatingly mounted thereon, said contact element having an opening encircling 75 said thimble portion larger in diameter than said thimble portion, an insulating washer snugly encircling said thimble portion, means on said contact element co-operating with said washer to prevent said contact element from touching said thimble, and an insulating abutment for said element on the side of said element opposite to the 80 side co-operating with said washer.

5. A jack of the character described having a metallic thimble portion, a contact element insulatingly mounted thereon, said contact element having an opening encircling 90 said thimble portion larger in diameter than said thimble portion, an insulating distance piece snugly encircling said thimble portion and peripheral means on said contact element co-operating with said distance piece 95 to prevent said contact element from touching said thimble.

6. A jack of the character described having a hollow metallic thimble portion through which a connecting plug is adapted 100 to project, a contact element insulatingly mounted thereon, said contact element having an opening encircling said hollow thimble portion larger in diameter than said thimble portion, an insulating distance piece 105 snugly encircling said thimble portion, and means on said contact element co-operating with said distance piece to prevent said contact element from touching said thimble.

7. A jack of the character described having a metallic thimble portion, a contact element insulatingly mounted thereon, said contact element having an opening encircling 110 said thimble portion larger in diameter than said thimble portion, an insulating washer 115 snugly encircling said thimble portion, and cup-shaped means on said contact element co-operating with said washer to prevent said contact element from touching said thimble.

8. A jack of the character described having a metallic thimble portion, a contact element insulatingly mounted thereon, said contact element having an opening encircling 120 said thimble portion larger in diameter than said thimble portion, an insulating washer snugly encircling said thimble portion, cup-shaped means on said contact element co-operating with said washer to prevent said contact element from touching said thimble, 125

and an insulating abutment for said element on the side of said element opposite to the side co-operating with said washer.

9. A jack of the character described having a metallic thimble portion, a contact element insulatingly mounted thereon, said contact element having an opening encircling said thimble portion larger in diameter than said thimble portion, an insulating distance piece snugly encircling said thimble portion, and cup-shaped means on said contact element co-operating with said distance piece to prevent said contact element from touching said thimble.
10. A jack of the character described having a metallic thimble portion, a contact element insulatingly mounted thereon, said contact element having an opening encircling said thimble portion larger in diameter than said thimble portion, an insulating washer snugly encircling said thimble portion, cup-shaped means on said contact element co-operating with said washer to prevent said contact element from touching said thimble, and an insulating abutment for said element on the side of said element opposite to the side co-operating with said washer, said thimble having means to secure said element, washer, and abutment in place thereon.
11. A jack structure of the character described comprising a hollow metallic thimble having means whereby it may be attached to a panel and having a rearwardly projecting hollow cylindrical portion through

which a connecting plug is adapted to project, a connecting spring insulatingly mounted on said rearwardly projecting portion and projecting rearwardly into the path of a plug, and an insulating member directly mounted on said portion for insulating said spring therefrom.

12. A jack structure of the character described comprising a hollow thimble portion having means whereby it may be attached to a panel and adapted to have a connecting plug projected therethrough, a contact spring insulatingly mounted on said hollow thimble having a portion thereof extending around said hollow thimble but spaced therefrom and a portion extending rearwardly into the path of a plug and means for maintaining said contact and hollow thimble portion in spaced relation.

13. An insulating mounting for a contact spring, comprising a base, a fastening element extending outwardly from said base, an insulating distance piece snugly encircling said fastening element, a contact spring superposed on said fastening element and having an opening larger than said element and smaller than said distance piece, said spring and distance piece having interlocking means to prevent electrical contact between said fastening element and spring at their area of juxtaposition.

In witness whereof, I hereunto subscribe my name this 4th day of May, A. D. 1926.

ALVA J. CARTER.
